UNITED STATES PATENT OFFICE.

GEORGE B. HAGGARD, OF WAYCROSS, GEORGIA.

FIREPLACE.

1,150,029.

Specification of Letters Patent. Patented Aug. 17, 1915.

Application filed January 10, 1914. Serial No. 811,355.

To all whom it may concern:

Be it known that I, GEORGE B. HAGGARD, a citizen of the United States, residing at Waycross, in the county of Ware and State of Georgia, have invented a new and useful Improvement in Fireplaces, of which the following is a specification, reference being had to the accompanying drawing.

My improvement relates particularly to a metal structure forming a fire place when such structure is suitably set in a recess in a wall and connected with a chimney flue.

The object of the improvement is to provide a structure composed of metal parts which may be easily and economically formed and conveniently assembled and placed in a wall to form an efficient heating apparatus.

In the accompanying drawings, Figure 1 is a front elevation of a little more than the left hand one-half of a fire place embodying my improvement, the line, *a—a*, being the upright middle of such a fire place, it being understood that the portion of the structure at the right of said line is a duplicate of the portion at the left of said line; Fig. 2 is a rear elevation of the portion of the structure shown by Fig. 1, the line, *a—a*, again indicating the upright middle of such structure; Fig. 3 is an elevation of the right hand side of the structure; Fig. 4 is an upright section on the line, *4—4*, of Fig. 1, looking toward the left; Fig. 5 is a horizontal section on the line, *5—5*, of Fig. 3; Fig. 6 is a horizontal section on the line, *6—6*, of Fig. 2; Fig. 7 is a section on the line, *7—7*, of Fig. 2; Fig. 8 is a section on the line, *8—8*, of Fig. 3; Fig. 9 is a rear view of one form of the upper back section detached from the other parts; Fig. 10 is a section on the line, *10—10*, of Fig. 4.

Referring to said drawings, *A, A*, are two side sections placed upright at the right and at the left of the structure with their lower ends resting upon the hearth or any other suitable support. The front edge of each such section is upright, and the lower portion of the rear edge of each such section is upright, while the upper portion of the rear edge slopes forward, as shown in Figs. 3 and 4. In the form shown in the drawings, the rear edges are set nearer to each other than are the front edges, so that said sections converge, going from the front rearward. The upright portions of the rear edges of said sections are

connected by a lower back section, *B*, which occupies the space between said edges and has its side edges joined to said rear edges by means of upright dove-tails, *1*, located on the upright edges of the section, *B*, and extending into upright dove-tail grooves, *2*, formed in the adjacent faces of the side sections. Above the rest position for each dove-tail, there is an opening, *3*, from the rear into the groove, *2*, large enough to allow the dove tail to pass forward into said groove when said back plate is moved forward from behind the side sections and high enough to bring the dove-tails opposite said opening.

Above the lower back section, *B*, and between the two side sections is the upper back section, *C*. On the upper portion of each side edge of such section, *C*, is an upright dove-tail, *4*, which extends into an upright dove-tail groove, *5*, in the adjacent face of the adjacent side section. Said dove-tail grooves are extended upward and widened above the rest position of said dove-tails. On account of the converging of the side sections and the sloping of the upper portions of their rear edges, said rear edges converge from above, and the side edges of the section, *C*, converge from its upper edge downward. This allows the insertion of the section, *C*, by moving it downward, the dove-tails, *4*, being made to enter the upper portions of the grooves, *5*, and then properly seated in the lower portion of said grooves, while the lower edge of said section is made to rest upon the upper edge of the lower back section, *B*. The upper edge of the section, *C*, extends only a little farther than the base of the damper hereinafter described.

To the front edge of each side section, *A*, is applied an upright face plate, *D*, each such plate rising from the hearth to the cross-face plate, *E*. For securing the face plates, *D*, each is provided on its rear face with rearward and downward directed hooks, *6*, each of which extends over a horizontal lug, *7*, formed on the outer face of the adjacent side section, *A*. Said lugs may be cast integral with the sections, *A*, and the hooks may be cast integral with the plates, *D*.

The cross-face plate, *E*, extends crosswise of the structure immediately above the upper ends of the face plates, *D*, and bears against the front edges of the side sections, *A*, and extends above said side sections and has a rearward-directed flange, *8*, extending

across a portion of the upper edges of the side sections, A. Each upright face plate has an upward extension, 9, over-lapping the rear face of the adjacent portion of the cross-face plate, E. Bolts, 10, extend through the plate, E, and said extensions and bind said plate firmly to the upright face plates. Thus said cross face plate and the upright face plates constitute a means for staying the front portions of the side sections.

A top plate, F, rests horizontally upon the upper ends of the side sections, A, and covers the portions of said edges which are not covered by the flange, 8. At its forward edge, said top plate has a flange, 11, which overlaps the flange, 8, to form a joint adapted to prevent the passage of smoke and ashes.

A little below and back of the level of the upper edge of the upper back section, C, a bearing, 12, is formed on the rear edge of each side section, A. Each such bearing is open, being in the form of a notch opening upward, and receives a journal, 13, on the adjacent lower corner of the damper, G, said damper having its lower and upper edges horizontal and being long enough to extend from one side plate to the other and wide enough to extend to or meet the rear edge of the top plate, F. Above each journal, 13, the metal is removed far enough to make room for the metal of the bearing behind the journal when the damper is turned back.

The structure is so set as to bring the damper into the lower portion of the chimney flue. When the damper rests on the side sections and against the top plate, as shown in Figs. 2 and 3, it is closed. It is to be put into this position when there is no fire in the fire place. Then the damper prevents the passing of air up or down through the flue and it intercepts soot falling in the flue. When the damper is turned rearward on its journals, as shown in Fig. 4, air and products of combustion may pass. For controlling the damper, the rear end of a latch bar, 14, is hinged to an ear, 15, which is set near one end and on the front face of the damper. A stud, 16, is located on the inner face of the adjacent side section, A, and the lower edge of the latch bar, 14, has notches, 17, adapted to receive said stud. Said notches are spaced upon said bar to engage said stud when the damper has been opened to different positions. Thus the damper may be set and secured in various positions, according to the amount of draft desired. And, on account of the open bearings in which the damper journals rest, the damper may be lifted into and out of position without disturbing other parts of the structure. By placing the bearing below and rearward of the upper edge of the back section, C, the damper is so located, when turned back, as

to be shielded by said back section from the intense heat.

In Figs. 2, 3, 4, and 8, the upper back section, C, is shown as having combined therewith a water back, 18, said back being cast across the lower portion of said section and integral therewith and provided at one end with two nipples, 19, for the connection of water pipes. A partition, 20, extends from a point in the water back wall between the nipples toward the opposite wall, so that water entering from one pipe must travel in a circuit through the water back before reaching the other pipe. It is to be observed that this water back and the remainder of said back section are formed independently of the other parts of the structure and may be removed from such other parts, and that the pipes which are connected with the water back are not connected with any other part of the structure. Above the water back, the section, C, has on its rear face oblique stiffening ribs, 21.

Fig. 9 shows the section, C, made without the water back and having the ribs, 21, extended downward to the lower edge of said section. The section, C, having the water back and the section, C, not having such water back are of the same length and width or of the same area and may be used interchangeably, so that a customer may buy and build into his structure either of such sections.

On the inner face of each side section is a grate lug, 22, and on the front face of the lower back section, B, are two forward-directed grate lugs, 23. The grate, H, has a horizontal portion, 24, resting on the lugs, 23, and an upright portion, 25, having rearward and downward directed hooks 26, extending rearward and downward over the lugs, 22. Said four lugs support the grate detachably, the latter being set into position after the other portions of the structure have been established. A screen, 27, having feet, 28, rests on the hearth a little way forward of the front portion of the grate.

I claim as my invention:

1. In a structure of the nature described, two upright side sections, a back section located between the rear edges of the side sections and detachably joined thereto, upright face plates detachably attached to the front edges of the side sections, a detachably-secured cross face plate extending across the front of said side sections above said upright face plates and having a rearward-directed flange extending over a portion of the upper ends of said side sections, and a top plate resting on the upper ends of said side sections rearward of said flange, substantially as described.

2. In a structure of the nature described, two upright side sections, a back section located between the rear edges of the side sec-

tions and detachably joined thereto, upright face plates detachably attached to the front edges of the side sections, a detachably-secured cross face plate extending across the front of said side sections above said upright face plates and having a rearward-directed flange extending over a portion of the upper ends of said side sections, and a top plate resting on the upper ends of said side sections rearward of said flange and a

hinged damper having its free edge meeting said top plate, substantially as described.

In testimony whereof I have signed my name, in presence of two witnesses, this sixth day of January, in the year one thousand nine hundred and fourteen.

GEORGE B. HAGGARD.
